Primary Examiner — Melanie H Tung*Assistant Examiner* — Bao-Yen Nguyen(74) *Attorney, Agent, or Firm* — Chiesa Shahinian & Giantomasini PC(57) **CLAIM**

The ornamental design for a keypad, as shown and described.

DESCRIPTION

Figure 1.1 is a front perspective view of a keypad according to our design;

Figure 1.2 is a top view thereof;

Figure 1.3 is a bottom view thereof;

Figure 1.4 is a rear view thereof;

Figure 1.5 is a front view thereof;

Figure 1.6 is a left side view thereof;

Figure 1.7 is a right side view thereof.

The broken lines illustrate portions of the keypad and form no part of the claimed design.

1 Claim, 7 Drawing Sheets(56)
